UNITED STATES PATENT OFFICE

GEDOR W. ALDEEN, OF ROCKFORD, ILLINOIS, ASSIGNOR TO AMERICAN CABINET HARDWARE CORP., OF ROCKFORD, ILLINOIS, A CORPORATION OF ILLINOIS

HINGE

Application filed January 29, 1930. Serial No. 424,162.

The invention relates to hinges particularly adapted for use in connection with certain types of furniture, such as drop-leaf tables or the like, and has as its general aim 5 the provision of a new and improved hinge which is simple in construction, may be easily incorporated as a part of the article of furniture, and may be cheaply manufactured.

In the production of drop-leaf tables certain manufacturing problems must be overcome, particularly in connection with the hinged mounting of the movable leaves of the table on the stationary part or top thereof. Thus, in one well known type of such a 15 table the meeting edges of the top and leaves are fashioned to provide complementary mating edges comprising a projecting bead having an arcuate surface on one part, and an arcuate bead-receiving recess in the other 20 part.

It is considered essential in such constructions that the exposed edges of the two parts be in close abutment substantially to eliminate any crack therebetween, when the leaves 25 are in either raised or lowered position. Heretofore, this result has been capable of attainment only by recessing or mortising the parts to receive the hinge members in order to position the pivotal axis of the hinge 30 substantially in the plane of one of the surfaces to which the hinge is attached. However, by such mortising, the table, as a whole, and particularly the edge which is beaded, is materially weakened and a further resulting disadvantage is that the mortising step 35 increases the cost of manufacture.

An object of this invention, therefore, is to provide a new and improved hinge for furniture in which the pivotal axis thereof 40 may be positioned substantially in the plane of one of the surfaces to which the hinge is attached without recessing or mortising the furniture.

Another object is to provide a novel hinge 45 capable of maintaining the mating edges of complementary arcuate surfaces in substantially close abutment.

More specifically, the invention contemplates, as an object, the provision of a hinge 50 in which the pivotal axis is located substan-

tially in the plane of the surface to which it is attached and in which the pivotal axis thereof has a movement of translation in said plane from one point to another during the relative movements of the hinge 55 parts.

The invention overcomes another production difficulty arising from the practice of shipping furniture of this nature in disassembled or "knocked down" condition. 60 That is, when the retailer or dealer receives a drop-leaf table the leaves are detached and separate from the top. Consequently, considerable care and skill is required in order that the leaves be mounted in proper relation on the top. It is, therefore, an object of the invention to provide a new and improved hinge in which the hinge members are separable so that each member may be secured to the top or leaves in proper relation and may be assembled by relative lateral movement of the top and leaves, other means being provided to prevent separation thereof after assembly.

A further object of the invention resides 75 in the provision of a hinge in which a portion of the surface to which the hinge is secured serves as a part of the pintle-receiving member of the hinge.

Still another object of the invention is to 80 provide a hinge comprising two hinge sections or members formed as complements of each other, each of which members are capable of being fashioned from ordinary sheet metal stock by a single die stamping operation.

Other objects and advantages will become apparent in the following description and from the accompanying drawing, in 85 which:

Figure 1 is a plan view on a diminished scale of the lower surface of a drop-leaf table showing hinges embodying the invention mounted thereon.

Fig. 2 is a separated plan view of one of 90 said hinges.

Fig. 3 is a side elevation of the hinge as seen when looking downwardly from the top of Fig. 1.

Fig. 4 is a view similar to Fig. 3 but show-

100

ing the hinge members in another position.

Fig. 5 is a longitudinal section taken substantially on the line 5—5 of Fig. 1.

Fig. 6 is a plan view of a modified form 5 of hinge.

Broadly, the invention contemplates a two-part hinge, each part of which may be fashioned from ordinary sheet metal stock by a single die stamping operation. One of said 10 parts, or hinge members, is bent to form a substantially U-shaped socket having an open side, which, when the part is attached to the furniture, abuts and is closed by a portion of the surface of said furniture. The 15 other of said hinge members includes a part fashioned as a pintle engageable with said socket by a relative transverse movement of the hinge members.

The socket and the pintle are formed to 20 provide an abutting holding engagement in two different positions of said hinge members, thus confining the movement of said members between two limits. Another part 25 of the pintle is shaped to rock over the portion of the surface of the furniture, which closes the open side of the socket, thus producing a translation of movement of the pivotal axis of the hinge from one point to another within the socket. The hinge members 30 are further provided with stop members which are operative at the limits defined by the engagements between the pintle and the socket.

Particularly describing the present invention, the hinge has been shown as used in connecting one of the leaves 10 of a drop-leaf table to the top 11 thereof. This form of furniture is arbitrarily chosen and it is not intended to limit the invention thereby. As 35 may be seen clearly in Figs. 3, 4 and 5, the particular type of drop-leaf table construction illustrated herein includes a laterally extending arcuately shaped bead 12 formed upon one of the table parts, in this instance, 40 the top 11, which bead is received in a complementary arcuately shaped recess 13 provided in the meeting edge of the other part. Usually the bead is somewhat longer than it 45 is thick so that the arcuate surface thereof 50 is not formed on a true arc of a circle.

The hinge, as has been mentioned, is formed in two parts comprising a socket presenting hinge member 14 and a pintle carrying hinge member 15 (Fig. 2). The socket presenting member 14 is in the form of a flat plate having suitable apertures 16 therein, through which screws 17 may pass to secure the member in place. One corner portion of 55 the plate is cut away to provide a recess 18 and the uncut portion of the plate is bent outwardly and thence inwardly to provide the opposite sides 19 and 20 (Fig. 5) of a substantially U-shaped socket 21. The open 60 side of the socket, when the plate is secured

to the top of the table, is closed by an abutting portion 22 thereof.

Preferably, the extreme end portion of the uncut part of the plate, adjacent the side 20 of the socket, is turned outwardly as at 23 to 70 abut the surface of the table top. If desired, one or more reinforcing bosses 24 may be provided on the sides of the socket during the formation thereof.

The pintle carrying hinge member 15 is 75 adapted to be secured to and carried by the leaf 10 which is hingedly connected to the top. The member 15 is in the form of a plate arranged to be secured by screws 17^a to the leaf near the adjacent meeting edge of the leaf so that a portion of said plate extends beyond said edge.

This portion has an elongated transversely extending recess 25 formed therein, the depth of which is substantially equal to the length 85 of the socket 21. That part of the plate intermediate the recess and the end of the plate constitutes a pintle 26 receivable in the socket 21 and the preferred arrangement is such that when the pintle engages the socket, the 90 side margins of the plates 14 and 15 are in substantial alinement.

In order to permit relative rotational movement of the pintle in the socket, the portion of the plate 15 which comprises a continuation 26^a of the pintle 26 is bent outwardly from the plane of the plate 15 to position the face of the pintle in angular relationship to the plane of the plate. This relationship will be determined by the character of the socket which is provided on the member 14. Thus, as an example, the present illustration embodies a socket in which the sides 19 and 20 extend at substantially 95 right angles to each other. The pintle, in such a case, extends at substantially 45° to the plane of the plate 15 so that when the pintle engages the socket, and the members 14 and 15 are in the same plane, the face of 100 the pintle abuts the nearer side of the socket, in this instance the side 20. It will be seen, therefore, that when the hinge members 14 and 15 are relatively moved to assume a position substantially at right angles to each other, the pintle 26 will move from its abutting position against the socket side 20 to a similar abutting engagement with the opposite socket side 19. Consequently, the pintle moves from one side of the socket to the other and determines, through its abutting engagement with one or the other sides, the extreme limits of relative movement of the hinge members 14 and 15. This movement, 105 therefore, may be termed a movement of 110 translation of the pintle from one point to another within the socket.

In order that the hinge may turn smoothly, and further to insure the proper positioning of the pintle within the socket at all times, 115

the face of the pintle which is opposite the socket engaging face thereof is arcuate across the width thereof, as may be seen at 27 (Fig. 5). Hence, as the hinge members move relatively, one portion of the arcuate face of the pintle is always in rolling or rocking engagement with the portion 22 of the surface which closes the open side of the socket.

Preferably, the arcuate surface of the pintle is so formed that the side margins of the pintle, during the relative movement of said members intermediate the two limits of movement, will be held in sliding engagement with the sides of the socket. To this end, the width of the opposite sides of the socket and the width of the flat face of the pintle are substantially equal. As a result of this construction, the side edges of the pintle are always in engagement with the surfaces of the sockets during the relative swinging movement of the members, all looseness or play between the parts is thereby eliminated and the pintle will move smoothly from one point to another within the socket.

From the foregoing, it will be apparent that a hinge has been provided which is capable of maintaining a close abutting relationship between the meeting edges of the two members which are hingedly connected thereby. This is especially evident (referring to Figs. 3 and 4) if the complementary interfitting parts are formed on an arc other than a true arc of a circle. In such a case, the transitory movement of the pintle during the movement of the members from the position shown in Fig. 3 to that shown in Fig. 4 shifts or carries the hinged table members inwardly so that the meeting edges of the members in both positions thereof substantially abut to eliminate cracks therebetween.

Preferably, auxiliary stop means are provided for supplementing the limiting engagement of the pintle with the socket members, since otherwise the pintle might accidentally be bent out of its normal operating position. To this end, the margin of the plate 15 adjacent the recess 25 and opposite the pintle 26 is offset outwardly, as at 28, to provide a flange positioned to overlie and abut the flat outer end 23 of the plate 14 when the hinge members are engaged and are in substantially the same plane. This abutting engagement of the parts 23 and 28 reinforces the limiting engagement of the pintle and socket when the pintle is in abutment with the socket side 20.

The auxiliary stop, for limiting the relative movement of the hinge members in the other direction, comprises a lug 29 extending outwardly from the continuing portion 26^a of the pintle. The lug 29 is arranged to move into overlying and abutting engagement with the outer surface of the plate 14 adjacent the recess 18 when the hinge members move to the position shown in Fig. 4. If de-

sired, a reinforcing boss 30 may be provided to strengthen this part of the hinge.

That the hinge, which has just been described, is well adapted for use where it is desired to ship the article of furniture in disassembled or knocked down condition is evident. Thus, taking the drop-leaf table, as an example, the manufacturer assembles the table complete at the manufacturing plant. In this way, the proper position of the drop-leaf relative to the table top is accurately and permanently determined by the skilled workmen in the manufacturing plant. This having been done, it is only necessary to move the table leaf laterally with respect to the top, whereupon the pintles slide out of engagement with the sockets and the table leaf is free to be packed separately.

Subsequently, when the furniture dealer is unpacking and assembling the table, it is only necessary to reengage the hinge members by a simple lateral movement in order to mount the leaf on the top. In order to prevent accidental lateral movement of the hinge members, a stop means is provided which normally holds the hinge members against the disengaging lateral movement but may be readily moved to an out-of-the-way position to permit said disengagement.

A preferred form of stop means is shown in Figs. 1 and 2 as comprising a flat bar 31 having an elongated, longitudinally extending aperture 32 therein. One end of the aperture is countersunk, as at 33, to receive the head of a screw 34 which extends through the aperture to secure the member to the top. The remaining portion of the aperture is of ample width to slidably receive the shank of the screw. The end of the bar, opposite the countersunk part of the recess, is bent to provide an arcuate boss 35.

In use, the bar is secured, by the screw 34, substantially in abutting engagement with the side of the hinge member 14 opposite the socket, in such manner that when the head of the screw 34 is in engagement with the countersunk portion 33 of the elongated slot 32, the boss 35 (see Fig. 1) is positioned adjacent the upturned portion 26^a on the hinge member 15. This abutting engagement prevents lateral movement of the hinge members 14 and 15.

When, however, it becomes desirable to disengage the hinge members, the screw 34 is loosened to disengage the head thereof from the countersunk portion 33 of the slot and the bar is then moved relative to the screw to move the boss 35 to an out-of-the-way position. Consequently, in permanently assembling the drop leaves on the table top, it is only necessary for the dealer to slide the bar 31 into its normal position and tighten the screw 34.

Referring to the modified form of hinge shown in Fig. 6, the essential parts of the

hinge are substantially the same. In this instance, however, the pintle is formed substantially centrally of the hinge member 15 by providing an elongated transversely extending aperture 36 in the plate. This positions the pintle 37 intermediate the sides of the plate 15 and correspondingly the socket member 38 is formed intermediate the sides of the plate 14. In this modification, the outwardly turned transverse continuations 39 on each side of the pintle 37 are provided with stop lugs 40, each of which functions in the same manner as the angular stop lug 29 in the first described form. In effect, therefore, the modified form embodies the principles of the hinge shown in Figs. 1 to 5, inclusive, with the addition of a second stop member for limiting the movement of the hinge members into the relative angular positions thereof.

In this modification, relative lateral movement of the hinge members 14 and 15 is not possible. Therefore, in preparing the table for disassembled shipment, the manufacturer permanently secures the hinge member 15 in place and marks or provides screw holes designating the proper position of the hinge member 14. In assembling, the dealer need only insert the end 23^a of the hinge member 14 underneath the flange 28^a and then secure the plate 14 in the designated position. Or, if desired, the screws holding the socket plate 14 may be merely loosened to allow the free end of the socket to move away from the table face far enough to permit insertion of the pintle, after which the screws may be tightened.

It will be apparent from the foregoing that a simple hinge has been provided which is well adapted for use in connection with drop-leaf tables, or similar articles of furniture, and which is of such similar construction that each part of the hinge may be fashioned by a single die-stamping operation.

I claim as my invention:

1. A hinge adapted to be secured to the surfaces of two parts to be connected comprising, in combination, a U-shaped socket member having an open side secured to one of said parts with the open side in abutment with the surface thereof, and a second member having a pintle thereon secured to the other of said parts, said pintle having a curved surface in rocking engagement with said socket abutting surface and being irregular in cross section for spaced engagement with opposed portions of said socket member.

2. A hinge adapted to be secured to the surfaces of two parts to be connected comprising, in combination, a pintle secured to one of said parts in overlying relation to the second part, said pintle having an arcuate face thereon adapted to rock over the surface of the underlying part, and a socket member

enclosing said pintle having an open side abutting the surface engaged by said pintle, said socket having engagement with said pintle to hold said pintle against said surface whereby the pivotal axis of said hinge is confined to the plane of the surface of said part.

3. A hinge comprising, in combination, a hinge member presenting a substantially U-shaped portion thereon having an open side adapted to be closed by the surface to which said member is secured, said portion being fashioned so that opposed sides thereof and said closing surface constitute a substantially triangular socket, and a second hinge member having a pintle receivable in said socket, said pintle having a flat face arranged to abut one or the other of two sides of said triangle, and having an arcuate surface rockable over the third side during the movement of said flat face.

4. A hinge comprising, in combination, a hinge member having a socket thereon, a second hinge member having a pintle thereon engageable with said socket upon relative lateral movement of said hinge members, and means on said socket carrying part arranged to engage said pintle carrying member to prevent endwise movement of the parts out of engagement.

5. A hinge for pivotally connecting two parts comprising, in combination, a hinge member secured to one of said parts having a socket thereon, a second hinge member on the other of said parts having a pintle thereon engageable with said socket upon relative lateral movement of said parts, and a stop member secured to said socket carrying part positioned to engage the side of said pintle carrying member away from said socket to prevent lateral movement thereof out of engagement with said socket.

6. A hinge adapted to be secured to the surfaces of two parts to be connected comprising, in combination, a socket member adapted to be secured to the uncut surface of one part within the margins of said part, a pintle member adapted to be secured to the uncut surface of the other part for engagement with said socket member, and means for confining the axis of pivotal movement of the members to the plane of the surface of one of the parts.

In testimony whereof, I have hereunto affixed my signature.

GEDOR W. ALDEEN.
